UNITED STATES PATENT OFFICE

LEONARD H. WHEELER, OF CHICAGO, ILLINOIS, ASSIGNOR TO STEWART-WARNER CORPORATION, OF CHICAGO, ILLINOIS, A CORPORATION OF VIRGINIA

PUMPING DEVICE

Application filed November 30, 1928. Serial No. 322,815.

The purpose of this invention is to provide an improved construction of a pumping device for developing vacuum or the status of sub-atmospheric pressure, in a chamber to 5 which the structure embodying the invention may be connected, the structure shown being particularly designed for connection with the vacuum chamber of a vacuum fuel feeding device commonly called "vacuum tank", for 10 producing the necessary vacuum therein for lifting fuel for an engine from a low level source; and for this use the invention as herein shown is arranged to be operated by a shaft of the engine reached by intrusion 15 into the crank case. In certain details the present device is designed particularly for avoidance of return to the crank case of the gases withdrawn from the vacuum chamber in developing the necessary vacuum 20 therein.

The invention consists in the elements and features of construction shown and described, as indicated in the claims.

In the drawings:—

25 Figure 1 is a vertical section of a pumping construction embodying this invention, the same being shown diagrammatically in relation to the crank case and to the vacuum tank with which it may be connected for 30 developing vacuum.

Figure 2 is a section at the line 2—2 on Figure 1.

Figure 3 is a section at the line 3—3 on Figure 1.

35 Figure 4 is a detail section showing a slight modification.

Figure 5 is a section at the line 5—5 on Figure 4.

40 Figure 6 is a view similar to Figure 1 showing a modified form of the device.

Figure 7 is an upper end plan view of this form.

Figure 8 is an elevation looking in the direction of the arrow, 6, on Figure 6.

45 Figure 9 is an axial section of the check valve fitting for connection with the discharge pipe, the same being shown in an enlarged scale.

50 Figure 10 is a section at the line 10—10 on Figure 9.

Referring to the drawings, the pumping device comprises a casing A, having a pumping cylinder, 20, with inlet port, 22, and inlet passage leading thereto from inlet pipe connection shown at 23, by way of port, 24, controlled by check valve, 25, opening for inflow and seating against reverse flow, the seat for the check valve being formed by counterboring the intermediate part of the inlet passage shown at 26, said counterbore being 55 shown at 27, and being closed by screwed-in plug, 28, having a terminal pin, 29, for limiting the opening movement of the check valve, the initial portion of the inlet passage, 23^a, from the intake pipe connection, 23, intersecting the bore, 24, at the lower end, and the final portion, 22, of the inlet passage which is bored in from the cylinder end parallel with the portion, 24, is connected with the latter above the check valve seat by boring in from 60 the outside to form the port of connection as seen at 22^a, the outer end of the bore being closed by plug, 22^b.

The casing A, comprises in addition to the piston cylinder 20, a passage 30 in a horizontal limb, A², said limb being provided for mounting the casing on the engine crank case and said passage, 30, leading to the outer end of the limb for registering with an aperture in the crank case at which the casing is to 75 be mounted.

The piston indicated at C, comprises an upper disc, c², and lower disk, c¹, and a cup leather, C¹, clamped between the disks with its cup flange folded downwardly, that is, 80 away from the inlet port of the cylinder.

The lower disk c¹, is dimensioned to allow the cup leather flange to be flexed downwardly inwardly, that is, slightly away from the cylinder wall so that the piston operates substantially as a check valve obtaining piston-wise fit of the cup leather only in the down stroke, which is the suction stroke, the cup leather yielding in the reverse stroke permitting the pumped fluid to pass by the piston 95 into the portion of the cylinder cavity and passage, 30, below the piston.

The piston is connected for actuation by its stem, C², to which at the lower end there is pivotally connected an operating lever, D, 100

which extends through the passage, 30, being fulcrumed at 50 toward the end of the limb, A², and projecting out from the open end of said limb for protruding into the crank case when the casing is mounted on the latter as above indicated, for which mounting it is provided with a flange, a², arranged to be secured by bolts in an obvious manner. It is contemplated that the lever, D, will be actuated by an eccentric cam G, on the shaft S, accessible to the lever at its intrusion into the crank case, the positive actuation thus derived being in with direction for giving the piston its suction stroke. The reverse stroke of the piston is produced by a spring, E, lodged at one end in the lower end of the casing where a seat is provided as seen at 35, the upper end of the spring is provided with a cap disk, 36, having a central depression for seating a downwardly projecting lug, d, on the inner end of the lever, D, by which the reaction of the spring is transmitted through said lever to the piston stem and piston for giving the latter its return stroke, in which, as above explained, the pumped fluid escapes past the check valve formed by the piston cup lever above described.

In view of the contemplated use of this pumping device for producing vacuum in the vacuum chamber of a vacuum tank, and in view of the fact that the gases withdrawn from such vacuum chamber for producing the vacuum are liable to consist of air more or less heavily charged with gasoline vapor, it is desirable to provide in the pumping device means for preventing this vapor to any substantial extent being fed into the engine crank case, as in the absence of provision to the contrary would result from the construction by which the casing is mounted on the crank case at an aperture through which the operating lever extends for protruding into the crank case to reach the operating cam. Means for preventing this delivery into the crank case of the gases pumped from the vacuum chamber, a vent port, 51, is formed at the lower end of the crank case and most conveniently at the foot of the seat, 35, in which the spring, E, is seated; and the passage, 30, is blocked for substantially defeating fluid communication between the cavity of the casing and the engine crank case by the construction of the lever and the portion of the casing at which the lever is fulcrumed, as will now be described.

The casing limb, A², at the locality of the fulcrum of the lever is formed with opposite inwardly protruding bosses, 52, 52, protruding toward each other and spaced apart a distance for admitting between them the lever, D, which is dimensioned for fitting thus between them snugly, but not to the impairment of its necessary pivotal action.

As designed and shown the lever is sub-

stantially square in cross section at this point but has projecting upwardly and downwardly from it bosses, 56, 56, which at their extremities are spherically arcuate about the intersection of the pivot axis with the axis of the passage, 30, which is cylindrical in form, these bosses being formed with lateral projections, 57, 57, at opposite sides projecting respectively above and below the inwardly protruding bosses, 52, of the casing member, A². For the purpose of conveniently forming the casing, A, by casting, and for that purpose designing it to make the necessary cores withdrawable, the bosses, 52, 52, are formed as seen in the drawings cylindrically curved at their outer ends and extending with the full diameter of the cylindrically curved ends, the entire length of the limb, A², of the casing, so that at their inner ends they terminate at the cavity which constitutes the piston cylinder; and this cavity, as will be seen from Figure 1, is arranged for withdrawal of the core by which it is formed, transversely with respect to the bosses, 52, 52; and it will be seen that this construction permits the making of the casing by casting. The form thus imposed upon the bosses, 52, as distinguished from the form of simple cylindrical bosses, which would serve the purpose of positioning and affording pivotal support for the lever, prevents completely blocking the passage through the limb, A², at the plane of the lever pivot as might otherwise be done by the extensions, 57, of the bosses, 56, extending above and below the bosses, 52, as mentioned, to the extent that these overhanging projections are necessarily spaced from the bosses, 52, which they overhang a distance sufficient to accommodate the angular movement of the lever by which it actuates the piston, the space thus allowed between the projections, 57, and the bosses, 52, being seen at 58 in Figure 1.

I do not limit myself to this particular expedient for blockading the passage, and another obvious method for accomplishing this result is illustrated in Figures 4 and 5, consisting of a sleeve, 100, dimensioned for fitting tightly in the passage, 30, and having pivot bearings, 101, for a pivot boss, 102, with which the lever is provided projecting at opposite sides and preferably spherical as shown, the sleeve being diametrically slit for assembling the two halves in engagement with the pivot boss before insertion of the sleeve with the lever into the passage, 30, wherein it may be permanently secured by the pin, 105.

The construction as first above described for blockading the passage, 30, at the pivotal mounting of the lever therein, is preferred notwithstanding the slightly incomplete blockade which it supports, merely by reason of the economy of construction when the casing, A, is designed for casting.

A simpler, and, on that account, a somewhat preferred form of this invention, is shown in Figures 6, 7 and 8. In this form the casing member, A^x, corresponding to the member, A, of the earlier figures consists of a sheet metal stamping having a check valve fitting, 21^x, screwed into its upper, otherwise closed, end. This fitting is formed to afford seat, as seen at 22^x, for an inwardly and down-
wardly opening—upwardly and outwardly seating—check valve, 25^x, which is retained in its chamber by a bushing, 22^x, drive-fitted in the lower end of the fitting, 21^x, said bushing having its upper end notched as seen at 22^x to adapt said bushing to stop the valve at open position without seating it, said valve being also peripherally notched as seen at 25^y, to afford clearance for the flow of the fluid around its periphery while it is centered in its chamber by approximately diametric fit therein.

In this modification, also, for simplicity of construction, the lever, D, is fulcrumed in the terminal portion of the casing member, 30. without provision for closing or approximately closing the entrance to said casing member which, on the contrary, is left open for free fluid communication with the crank case when the device is mounted on the engine as described. For thus fulcruming the lever in the end of the casing member has interiorly projecting bosses, 52, as in the form shown in the earlier figures, and the lever is provided with bosses, d, of substantially the same diameter as the bosses, 52, and dimensioned for fitting snugly between the latter when the lever is connected to the casing by the pivot pin, 50.

I claim:—

1. A pumping device for service in connection with an engine having a pump cylinder and a piston member consisting of two rigid disks and a cup leather clamped between them, both disks being substantially less in diameter than the cylinder cavity, the disk at the inner side of the cup leather being substantially less in diameter than the other disk and substantially less than the inner diameter of the cup leather, whereby the cup leather is adapted to act as a check valve for passing the fluid pumped from the side opposite the cup cavity to the other side, the pump cylinder having inflow connection at the side of the piston opposite the cup cavity of the cup leather, and a check valve controlling said inflow connection opening for inflow and seating against reverse flow, and engine-operated means for reciprocating the piston connected therewith for said operation at the side opposite the outflow connection.

2. A pumping device adapted to be mounted on an engine for producing vacuum to serve the operation of the engine, said device comprising in combination with a pump cylinder, a piston member having its peripheral

portion resiliently flexible radially normally seating throughout its circumference on the cylinder wall and trending in one direction longitudinally of the cylinder throughout its whole circumference, whereby it is adapted at a marginal circumferential part to yield inwardly and in said longitudinal direction when the piston is moved in the opposite direction; the pump cylinder having inflow connection at the side of the piston opposite said direction of trend; a check valve controlling said inflow connection opening for inflow and seating against reverse flow, and engine-operated means for reciprocating the piston.
